PAGE 2

FIGURE 1 is a front perspective view of an automobile with convertible hard top with the top up embodying my design;

FIGURE 2 is a rear perspective view thereof; and

FIGURE 3 is a side view of the automobile with convertible hard top with the top down.

The broken lines represent portions of the automobile visible through the windshield and side windows. The undisclosed side of the automobile is a mirror image of the side shown.

I claim:

The ornamental design for an automobile with convertible hard top, as shown and described.
